UNITED STATES PATENT OFFICE.

ALVIS F. CROOM, OF DALLAS, TEXAS.

PROJECTILE.

SPECIFICATION forming part of Letters Patent No. 677,179, dated June 25, 1901.

Application filed October 19, 1900. Serial No. 33,633. (No model.)

To all whom it may concern:

Be it known that I, ALVIS F. CROOM, residing at Dallas, in the county of Dallas and State of Texas, have made certain new and useful Improvements in Projectiles, of which the following is a specification.

It is the object of my invention to provide an improved form of projectile for use in smooth-bore guns of any caliber, the same being so grooved or rifled as to insure rapid rotation and great accuracy and range in flight.

The construction I have adopted is shown in the accompanying drawing, in which a side view of my projectile is represented.

The cylindrical body and conical point of the projectile are provided with two opposite spiral semicircular grooves *f*, extending to points adjacent to the rear end and having a uniform width and gradually diminishing in depth from front to rear. The width of the grooves *f* is such that each occupies one-fourth of the circumference of the projectile. It will be seen that the cylindrical butt of the projectile having a flat end dispenses with the necessity for use of a sabot in smooth guns. A projectile thus provided with grooves when fired from a smooth-bore firearm will rotate once in every eight or ten inches of its flight and maintain a flat trajectory for a comparatively long distance. In other words, the projectile will have the same rotary or spinning motion, and therefore the same accuracy, when

discharged from a smooth-bore gun as one from a gun having a rifle-bore, while the trajectory will be flatter and the range greater, 35 since a ball shot from a smooth bore encounters less friction and resistance, and therefore attains a greater velocity with a given pressure of explosive gases. The economy of time, labor, and expense in the manufacture 40 of smooth-bore guns as compared with rifled ones also adds to the practical importance of a grooved projectile.

The projectile may be used in a rifled gun; but it would be desirable in such case to have 45 a disk or sabot provided with radial projections to fit the grooves.

What I claim is—

As an improved article of manufacture, the projectile hereinbefore described, the same 50 having a conical point and a cylindrical body which is of uniform diameter throughout its length, and provided with two semicircular spiral grooves arranged diametrically opposite, and extending from the apex to points 55 adjacent to the butt and gradually diminishing in depth toward the butt which is made cylindrical and flat at the end, as shown and described.

ALVIS F. CROOM.
